R. F. ROBB,
ARTIFICIAL TOOTH,
APPLICATION FILED FEB. 28, 1916.

1,240,258.

Patented Sept. 18, 1917.

Inventor:
Robert Finlay Robb
By R. Singew. atty.

UNITED STATES PATENT OFFICE.

ROBERT FINLAY ROBB, OF GLASGOW, SCOTLAND.

ARTIFICIAL TOOTH.

1,240,258.

Specification of Letters Patent. Patented Sept. 18, 1917.

Application filed February 28, 1916. Serial No. 80,915.

To all whom it may concern:

Be it known that I, ROBERT FINLAY ROBB, of 125 Great Western Road, Glasgow, Scotland, dentist, have invented certain new and 5 useful Improvements in or Relating to Artificial Teeth, of which the following is a specification.

My invention relates to improvements in dentistry and has for its object to simplify 10 the fixing of the teeth to the plate without the use of platinum wire, and thereby reducing the cost of the same, and refers to that class in which there is cut in rear or back wall at the back of the tooth a longitudinal slot or slots adapted to receive the vulcanite forming the plate and in which there 15 is carried a metal attachment of aluminum or other suitable metal which the acids of the mouth will not touch, the slots and mid-dle attachment being so formed as to dovetail one within the other, thus the pins grip the tooth and the cross-bar is attached to the plate.

In order that my invention may be prop- 20 erly understood and readily carried into effect, I have hereunto appended one sheet of drawings, of which—

Figure 1 is an elevation of the back of an 25 artificial tooth detached designed for the upper jaw embodying my invention.

Fig. 2 is a side view of the same with a part of the denture plate in section.

Fig. 3 is a plan also of Fig. 1, looking from front to back.

Fig. 4 is a horizontal section of Fig. 2 taken on the line *a*, *b*.

Fig. 5 is a plan of the aluminum or other metallic pin or attachment device detached.

Fig. 6 is a view corresponding to Fig. 1 40 of an artificial tooth designed for the lower jaw and embodying my invention.

Fig. 7 is a side view corresponding to Fig. 2.

Fig. 8 is a plan of the same correspond- 45 ing to Fig. 3.

Fig. 9 is a horizontal section correspond- 50 ing to Fig. 4 taken on the line *c*, *d*, of Fig. 7.

Fig. 10 is a plan of the attachment device corresponding to Fig. 5, and

Fig. 11 is an end view of same, all of the 55 aforesaid figures are drawn to an enlarged scale and all hereafter more fully referred to and described.

With reference to Figs. 1 to 5 inclusive 55 of the drawings which appertain to the upper denture plate, and although the tooth

illustrated in these figures is the incisor tooth, it is here explained that my improvements apply equally to a canine or molar tooth or any number of teeth composing a 60 complete set. I cut in the rear of back wall of the tooth a deep incision to the extent of half its depth, which operation leaves a well defined shoulder or recess to receive a considerable bed of vulcanite. In the rear wall 65 as formed by said incision, I cut two vertical parallel grooves or dovetail recesses *A* and *B* within the back wall or lingual side thereof, and above the shoulder *C* of the tooth *D*, extending in a right angular direction 70 as shown at *A*². These grooves or dovetail recesses aforesaid are designed to receive corresponding dovetail projections *E* forming a part of the metallic attachment, and the remaining space to be filled up by 75 the vulcanite. The said metallic attachment in one of its forms consists of the said projections *E*, the two arms *F*, *G*, and cross-bar *H*. In the intimate adherence of the vulcanite *I* or the like to the tooth, the metallic 80 attachment is placed approximately in the position shown in Fig. 2, and portions of the vulcanite *I* or the like are pressed into the dovetail recess above and below the projections *E* and so perfectly interlock the elements together, even with the usual shrinkage of the vulcanite.

Referring to Figs. 6 to 11 inclusive of the drawings which illustrate the application of the improvements to the lower plate of the 90 mouth, the tooth there shown is of a similar type to that illustrated in the preceding figures, and though shown in the same position it would in practice be inverted, in which instance a single vertical groove or dovetail 95 recess *A*¹ is cut within the back wall and extending in a right angular direction at the shoulder as at *A*². Into the vertical portion of this groove or recess is inserted the dovetail projection *E*¹ of the metallic attach- 100 ment which, in its simplest form, consists of a dovetail formed on both of its sides as seen in Fig. 11 and of the arm *F*¹, and a short transverse piece *H*¹, projecting on either side of the aforesaid arm. In like manner to the 105 method employed corresponding to Figs. 1 to 4, the vulcanite is pressed into the recess *A*¹, above and below the dovetail projection *E*¹ and the arm *F*¹ and bar *H*¹, and the whole 110 completely enveloped as seen in Fig. 7.

Claims:

1. The combination with an artificial

- tooth having a horizontal shoulder projecting from its rear wall, the rear vertical wall of the tooth and the face of said shoulder having a plurality of aligned dovetail grooves 5 therein, of a locking bar having a plurality of projections in locking engagement with the grooves of said tooth.
2. An artificial tooth having a plurality of dove-tailed grooves in the rear wall there- 10 of, and a locking bar adapted to be seated

in a bed of vulcanite or like material, said locking bar having a plurality of projections for engaging in said grooves.

In witness whereof I affix my signature in presence of two witnesses.

ROBERT FINLAY ROBB.
